UNITED STATES PATENT OFFICE.

MINOR STRANG, OF TECUMSEH, MICHIGAN.

ELECTRIC-RAILWAY SAFETY SYSTEM.

1,126,122.

Specification of Letters Patent.

Patented Jan. 26, 1915.

Application filed July 29, 1912. Serial No. 712,089.

To all whom it may concern:

Be it known that I, MINOR STRANG, a citizen of the United States, residing at Tecumseh, in the county of Lenawee and State of Michigan, have invented certain new and useful Improvements in Electric-Railway Safety Systems; and I do hereby declare the following to be a full, clear, and exact description of the invention, such as will enable others skilled in the art to which it appertains to make and use the same.

This invention relates to improvements in safety appliances for electrical railroads and more particularly to a safety and signaling system for blocks between siding or "turn outs" of an electrical railway,—one object of the invention being to provide means whereby sections of the trolley wire or third rail will be automatically segregated so as not to supply current to the motors of cars approaching the sidings when another car is in the block between two sidings.

A further object is to so construct and arrange a safety system of the character specified that several cars traveling in the same direction in comparatively close proximity to each other, will be permitted to pass from one block to another without taking the siding, and so that the danger signal at this end of the block will be reset and the segregated trolley wire section made "dead" after each of the group of cars has passed, for cars running in the opposite direction, until the last of the several cars shall have passed.

A further object is to provide a safety system for electric railways embodying "safety" and "danger" signals; means for automatically segregating portions of the supply conductor, and means for effecting the automatic application of the car brakes if a car should, by its momentum, pass a segregated trolley wire section when the same is "dead."

With these and other objects in view, the invention consists in certain novel features in the arrangement and coöperation of devices and electrical circuits as hereinafter set forth and pointed out in the claims.

In the accompanying drawings, Figure 1 is a diagrammatical view illustrating my improvements, and represents a block of railway between two "sidings" or "turn-outs." Fig. 2 is a fragmentary view showing the track contact devices, shoes on a car

to coöperate therewith, and the brake applying mechanism. Fig. 3 is a view of a signal tower.

1 represents a block of electric railway between two sidings or turn-outs 2 and 3, the block thus extending from one siding to another. My improvements are adaptable for use on a road employing as a supply conductor, a trolley wire or a third rail, but for convenience, I have illustrated in Fig. 1 of the drawing, a trolley wire 4. Near each end of the block (adjacent to the respective sidings 2—3) sections 5 of the trolley wire are electrically segregated from the main portions of the wire, by means of suitable insulating inserts 6. Near each block terminal a signal tower 7 is located and each of these is provided with a danger signal 8 and a safety signal 9. Each signal tower may be conveniently made hollow and constructed with suitable compartments for the housing of various instruments, herein-after explained. Each segregated trolley wire section 5 is shunted by means of a conductor 10 so as not to interfere with the electrical continuity of the trolley wire circuit and each section 5 is connected, by a conductor 11 with a contact 12 of a relay 13. This relay comprises two solenoid coils 14—15 in which a core member 16 (common to both coils) is movable. The lever 17 of the relay, which is pivoted at 18, is disposed between the two coils and loosely connected, between its ends, with the core member 16. The lever 17 is provided near its upper end with a contact point 19 to engage the contact 12, and this lever also has secured thereto, a block 20, of insulating material, to move a spring finger 21 into electrical contact with a finger 22. The lever 17 is also provided with a contact point 23 to engage a contact 62. A spring 25, fixed at one end to a suitable support, is attached at its other end to the lever 17 in such manner as to retain said lever in the position to which it may be moved by the solenoids and thus insure the effectiveness of the electrical contacts controlled by said lever.

A relay, such as above described is contained within each tower 7, and the latter also contains an instrument 26, comprising two solenoid coils 27—28, the cores 29—30 of which are pivotally connected with pivoted arms 31—32, said arms being movable in one direction by the solenoids and in the

reverse direction by springs 33. The arms 31-32 are provided with dogs 34-35 adapted, respectively, to coöperate with ratchet teeth 36-37 on a disk 38, the two sets of teeth being so arranged that the dog 34 will operate to turn the disk 38 in one direction, and so that the dog 35 will operate to turn said disk in the opposite direction. The disk 38 is mounted on a suitable spindle 39 and carries a cam 40, with which latter, a pivoted arm 41 (having a roller 42) coöperates. The arm 41 is maintained in operative relation to the cam by means of a spring 43, and carries a contact 44 to engage a contact 45, said arm and contacts constituting a circuit closer for a purpose hereinafter explained.

At each block terminal, contact rails 46 and 47 are located at respective sides of the track, one of said contact rails 46 being in position to be engaged by a pivoted, spring-pressed shoe 48 carried by a rolling equipment 49, running in one direction, and the contact rail 47, being in position to be engaged by said pivoted contact shoe when the rolling equipment is traveling in the reverse direction, and both of these car shoes are electrically connected with the trolley. Another contact rail 50 is also located adjacent to the track at each block terminal to be engaged by the shoe 48, for a purpose hereinafter described, and a fourth contact rail 51 is provided at each block terminal to be engaged, under certain conditions, by a separate spring-pressed pivoted shoe 52 on the rolling equipment. Chains or ropes 53 are connected with the shoes 48 and 52 for the purposes of raising them out of reach with the contact rails when desired to do so.

For convenience, the block terminals shown in Fig. 1 at the respective sidings, may be designated A and B.

45 A conductor line 54 is connected with the contact rail 46 at B and, extending to the block terminal A, is connected with one terminal of solenoid coil 27. The other terminal of this coil is connected by a conductor 55 with one terminal of solenoid 14 of relay 13, and
50 with the other terminal of this solenoid, a conductor 56 is connected. A conductor 57 electrically connects the conductor 56 with one of the track rails. From the juncture of the conductors 56 and 57, a conductor 58 extends to, and is connected with, one terminal of the coil of the solenoid 28, and the other terminal of this coil is connected, by a conductor 59, with the contact rail 50.

60 Normally, when the block is clear, a circuit will be closed at contacts 12-19 of relay 13, to render active or put current on the segregated trolley wire sections 5, so that a car may proceed past the same. This circuit may be traced as follows: from the 65 trolley wire, at the left of the siding ter-

minal at A, by means of a conductor 60 to lever 17 of relay 13, to relay contact 12, and then by conductor 11 to the trolley wire section 5. A branch 11^a—11^b from this circuit includes a safety signal 11^c. When a car (running in the direction of the arrow in Fig. 1) passes the block terminal B, and the car shoe 48 engages the contact rail 46 at B, a circuit will be established from the trolley wire through car shoe 48 and contact rail 46 at B to the first described circuit, and the solenoids 14 and 27 (at A) will be energized. When the solenoid 14 is thus rendered active, the relay lever 17 will be moved to the position shown at station A, thereby open-circuiting the trolley wire section 5 at A, and at the same time closing a circuit through a danger signal 61. The danger signal circuit includes the contact 23 of relay lever 17, a contact 62, connected by a conductor 63 with one terminal of the signal, and a conductor 64 connecting the other terminal of the signal with a track rail. When the relay lever 17 is moved to the position shown at the A-end of the block, the finger 21 will be moved into contact with the finger 22 and establish a partial circuit including contact rail 51, a conductor 65, fingers 21—22 and a short conductor 66 connecting the finger 22 with conductor 64. The west bound car (indicated by the arrow) now occupies the block, and an east bound car arriving at A, will find a danger signal set against it and will also be prevented from proceeding into the block, by reason of the fact that the segregated trolley wire section 5 will be dead; the circuit which supplies this trolley wire section being open at contacts 12—19 of the relay. Should the motorman of the east-bound car fail to observe the danger signal, and permit his car to run with sufficient momentum (as on a down grade) to pass the trolley wire section 5, the car shoe 52 will make contact with the contact rail 51 and complete the partial circuit 65—66—21—22—64, through a conductor 67, a solenoid 68 on the car and a conductor 69 connected with the trolley. The solenoid 68 controls a latch 70 which engages a spring-actuated lever 71 on the valve 72 in the air brake pipe 73. It will be apparent that when the circuit of the solenoid 68 is completed as above explained, (upon the arrival of the east-bound car at the contact shoe 51,) said solenoid will operate to actuate the latch 70 and release the air brake valve, thus causing the automatic application of the brakes. When the east bound car reaches the block terminal A, and finds the devices set at danger, this car will be backed onto the siding. The shoe 48 on the west-bound car, upon approaching the A-end of the block will engage the contact rail 47 for the purpose of reversing the relay and rendering

active the wire section 5 at A. This result is accomplished by energizing the relay solenoid 15 through a circuit which may be described as follows: from the trolley wire 5 through car shoe 48 to contact rail 47; then by a conductor 74 to solenoid 15; from the latter, by conductor 75 to conductor 57, and by the latter to the track rail. The energizing of the relay solenoid 15 will cause the lever 17 to move to position to close the contacts 19-12 and thus close the circuit which supplies current to the segregated wire section 5 at A. The west-bound car 10 may now proceed. It will be understood that when the east-bound car passes through the block the circuits and devices at B will be operated precisely as hereinbefore stated in describing the operation of the devices at A. Should cars reach respective ends of 15 the block at the same time, the danger devices at both ends of the block would be set. One car or the other would be entitled to the right of way by prearranged orders, and the conductor of the car having the 20 right of way will be enabled to render active the wire section 5, by closing a hand switch 76,—said switch being held normally open by means of a spring 77. The movable arm of this switch comprises two conductor members 76^a, 76^b connected by wires 25 78, 78^a with the trolley wire, and the stationary contact 79 of said switch is connected by a conductor 80 with the conductor 74, while the stationary contact 79^a is 30 connected by a wire 79^b with conductor 59. It is apparent that when the switch 76 is closed on the contact 79, the solenoid 15 will be energized and the circuit which renders the wire section 5 active, will be closed at 35 40 12-19. When the switch 76 is closed, a circuit will also be established from the supply conductor by conductors 78, 78^a and 79^b to conductor 59, through solenoid 28 to conductor 58 and from the latter to the track 45 rail by way of conductor 57. This will energize solenoid 28 and cause the disk 38 to be moved back one tooth, said disk having previously been moved forward by the action of solenoid 27, when the car entered the 50 B-end of the block. It is sometimes desired to run several cars close together in the same direction before permitting any cars to pass over a block in the opposite direction. It is to permit such operation of the 55 line that the instrument 26 is provided. When a west-bound car passes the track shoe 46 at B, and causes the operation of the relay 13 at A, as before described, the solenoid 27 of instrument 26 at A will also 60 be energized and cause the dog 34 to engage a tooth 36 of disk 38, the distance of one tooth. This will not however be sufficient to release the arm 41 from the larger part 65 of the cam 40. When the second car enters the block at B, the solenoid 27 will be

again energized and the disk 38 will be moved another tooth, the cam now permitting the arm 41 to drop and the contact 44 on said arm to engage the contact 45. The contact 45 is connected by a conductor 80 70 with the conductor 55, and the arm 41 is connected by a conductor 81 with the conductor 59. The disk will be successively operated, tooth by tooth, in the same direction until all the cars of the group have entered the block. When the west-bound cars pass the A-end of the block, each will first operate the relay 13 as before described to render active the segregated wire section 5, to enable it to pass to the next block. 75 Then, as each car passes the track shoe 50, two parallel circuits will be established, one through the relay solenoid 14 for resetting the devices at danger, and the other circuit will energize the solenoid 28 (which 80 is a slow-acting solenoid) for the purpose of causing dog 35 to engage the teeth 37 of disk 38 and return said disk, (step by step as the several cars pass), to its normal position. The parallel circuits, above referred 85 to, may be traced as follows: The circuit of relay solenoid 14 may be traced from contact rail 50 by conductor 59 to X; then by conductor 81 to arm 41, to contact 45, to conductor 80; by conductor 55 to solenoid 90 14; then by conductor 56 to conductor 57, and by the latter to a track rail; the other parallel circuit including the solenoid 28 of instrument 26 may be traced from point X 95 on conductor 59 to solenoid 28 and from 100 the latter by conductor 58 to conductor 57. When the last car of the group has passed the block terminal, the instrument 26 will have been reset to its normal position and the devices will remain at safety, with the 105 safety signal 11^c set and the segregated wire section 5 rendered active.

It will be understood that the various instruments, devices and circuits will be provided for each block terminal and that they 110 will be operated automatically as hereinbefore described for cars traveling in either direction.

Should the trolley wheel of a car going in one direction accidentally reach or pass 115 the insulated section of the trolley wire, and travel upon the track or block which is occupied by other cars traveling in an opposite direction, said first named car can be returned to the siding by having an attendant press the conductor's switch. This leaves the signals set to safety, but the first named car does not dare proceed until the cars that are already on the block have 120 passed through.

Having thus fully described my invention, what I claim as new and desire to secure by Letters Patent is:—

1. In an electrical railroad block system, the combination with a block of railroad, a 130

- supply conductor provided with electrically segregated portions, conductors shunting said segregated portions of the supply conductor, rolling equipment and a contact shoe 5 carried by the latter and connected with a source of electrical supply of track contacts at the entrance and exit ends of the block, a relay provided with a plurality of coils positioned at the exit end of the block, a 10 partial circuit including one coil of said relay and a track contact at the entrance end of the block, a partial circuit including another coil of the relay and a track contact at the exit end of the block, a circuit including the separable contacts of said relay and connecting the main supply conductor with the segregated portion thereof, a branch leading from said last mentioned circuit, to and including a safety signal, and a branch 15 circuit including a manually operated switch forming a secondary connection between said relay and the supply conductor whereby the system may be manually controlled.
2. In an electrical railroad system, the 20 combination with a block of railroad, a supply conductor provided with electrically segregated portions at each end of the block, conductors shunting said segregated portions of the conductor, and rolling equipment, of a relay at each end of the block, means controlled by the rolling equipment for operating said relays, a plurality of 25 circuits including the separable contacts of said relays and connecting the main conductor with the segregated portions thereof, a shoe carried by the rolling equipment, a partial circuit including said shoe, an electromagnetically-controlled valve in the brake system of the rolling equipment and included in said partial circuit, track contacts 30 in advance of the segregated conductor sections, a partial circuit including said track contacts, and circuit closures controlled by the relays and included in said last-mentioned 35 partial circuits.
3. In an electrical railroad system, the combination with a block of railroad, a supply conductor provided with electrically segregated portions at each end of the block, 40 conductors shunting said segregated conductor sections, and rolling equipment, of circuits connecting the main conductor with said segregated portions thereof, means controlled automatically by the rolling equipment for opening and closing said circuits, and a normally open manually-operated 45

switch positioned in branch circuits at each end of the block for manually controlling the closing of said circuits, said branch circuits forming secondary connections with the supply conductor. 50

4. In an electric railroad system, the combination with a block of railroad, a supply conductor provided with an electrically segregated section adjacent one end of the block, a conductor connected around said segregated section, a connection between the main supply conductor and the segregated section, a switch and a step by step mechanism controlling the same, a circuit including a danger signal, means controlled by a car entering the block at the other end for opening said connection and closing the danger signal circuit and for operating said step by step mechanism in one direction, 70 said switch being moved to operative position only upon subsequent operations of the step by step mechanism after the first, and means controlled by a car passing out of the block for first closing said connection and 75 then opening said connection, provided the switch is in operative position, and for operating said step by step mechanism in a reverse direction. 80

5. In an electrical railroad system, the combination with a block of railroad, a supply conductor provided with electrically segregated portions at respective ends of the block, conductors shunting said segregated portions of the supply conductor, and 90 rolling equipment, of a circuit at each end of the block connecting said segregated portions with the supply conductor, circuit opening and circuit closing means controlled by the rolling equipment adapted to open 95 and close said circuits, a partial circuit at the exit end of the block and including said circuit opening means, a circuit closer in said partial circuit, electromagnetically operated means controlled by the rolling equipment entering the block for closing said last-mentioned circuit closer, and electro-magnetically operated means controlled by the rolling equipment leaving the block for opening said last-mentioned circuit closer. 100 105

In testimony whereof, I affix my signature, in presence of two witnesses.
